METHOD AND APPARATUS FOR DETERMINING WATER CONTENT OF CONCRETE IN THE FLUID STATE

Gordon Lindsay Glegg, Kingston Hill, England, assignor of one-half to The Square Grip Reinforcement Company (London) Limited, London, England

Application July 27, 1949, Serial No. 107,105
In Great Britain July 28, 1948

3 Claims. (Cl. 175—183)

1

This invention relates to methods of determining the water content of concrete masses when in a fluid condition.

Hitherto, it has been the practice to estimate the water content of a concrete mass when in a fluid condition by determining the slump value of the concrete. This is an indirect method of estimating the water content of fluid concrete and furthermore slump values give only a rough guide as to the actual water content of the concrete.

It is an object of the present invention to evolve a method of rapidly and accurately determining the water content of any given mass of concrete when in a fluid condition.

According to the present invention there is provided a method determining the water content of a mass of fluid concrete which consists in vibrating the fluid concrete until the constituents thereof segregate, the heavier constituents falling to the bottom of the mass whilst the lighter constituents remain at and rise to the upper zone of the mass and which method further consists in inserting two spaced electrodes in the mass in the zone in which the lighter constituents tend to segregate, a known E. M. F. being applied across the electrodes and measurements being made of the maximum current passing between the electrodes during the vibrating operation, the maximum current value being used as an indication of the water content of the mass of fluid concrete.

For a better understanding of the nature of the invention and to show how the same may be carried into effect reference will now be made to the accompanying drawings in which,

Figure 1 is a diagrammatic layout of apparatus for carrying out the method of the invention, partly in section,

Figure 2 is a circuit diagram of the apparatus shown in Figure 1 and

Figure 3 shows an alternative form of vibrator mechanism.

The invention relies upon the observation that whereas a mixture of cement and water has a relatively high electrical conductivity, the other constituents of a concrete mix (sand and ballast) are practically non-conductive. When concrete is consolidated by vibration using for example, a vibrating appliance such as that described and illustrated in U. S. Patent No. 2,490,122 the pockets of occluded air which occur during the shovelling or pouring of a wet aggregate are gradually eliminated. If the vibration is continued after all the pockets of occluded air have

2

been eliminated, the homogeneity of the aggregate is destroyed as the heavier constituents thereof gravitate toward the bottom of the mass leaving at the top surface only a thin aqueous slurry. The electrical resistance of the surface mixture will vary with the amount of water present for a given mix and accordingly if the proportions of cement and sand are known it is possible to ascertain, from a measurement of the electrical resistance, the water-cement ratio, which is the chief factor in deciding the strength of the concrete after setting. It is important that the vibration of the mix should be continued for a period sufficient to ensure 15 segregation, since the presence of larger aggregates in that portion of the mix under test would introduce unknown factors which would render the accurate calculation of the water-cement ratio impossible.

20 In Figure 1 there is shown an apparatus for carrying out the determination of the water content of a mass of fluid concrete. This apparatus comprises a container 1 having two electrodes 2 and 3 secured to the underside thereof, and provided with a handle 4. Inside the container there is located an electric motor 5 which drives a shaft 6 having an eccentrically mounted weight 7 mounted thereon. The handle 4 is provided with a press button switch 8. A flexible cable 9 connects the handle 4 to a case 10, which contains (see Fig. 2) a battery 11, an ammeter 15 and resistances 12, 13 and 14. The case also contains a two-way switch 16 and a control knob 17A for adjusting the voltage.

35 The elements of the apparatus described above are connected as shown in Figure 2. The resistances 12 and 13 are connected directly across the battery 11 through the switch 8. The resistance 13 has a sliding contact 17 which can be moved by means of the knob 17A. The sliding contact is connected to one terminal 18 of the ammeter 15, the other terminal 19 of which is connected to the contact 20 of the two-way switch 16. The contact 20 can co-operate with 40 either the contact 21 or 22. The contact 22 is connected through a high resistance 14 to the negative terminal of the battery 11. The contact 21 is connected to the electrode 2 and the electrode 3 is connected directly to the negative 45 terminal of the battery. The electric motor 5 is connected through the switch 8 across the terminals of the battery 11.

Instead of using the motor 5 driving an eccentric weight 7, it is possible to use a vibrating 50 mechanism as indicated in Figure 3. This vi-

brating mechanism comprises an iron armature 23 mounted pivotally on a fixed pin 23A, the said armature having two prongs 24 and 25 at one end thereof. The prong 24 carries a contact 26 and the prong 25 carries a contact 27. A fixed contact 28 is disposed to lie between the contacts 26 and 27. The end 29 of the armature 23 lies between two coils 30 and 31, each of which is wound on an iron core. One end of the coil 31 is connected to the positive terminal of the battery 11 and the other end of the coil is connected to the contact 27. One end of coil 30 is connected to the positive terminal of the battery and the other end of the coil is connected to the contact 26. The contact 28 is connected to the negative terminal of the battery 11 through the switch 8. Condensers are connected across the contacts 26 and 28, and 27 and 28.

In operation this vibrating mechanism functions as follows. When the contact 26 encounters the contact 28 the coil 30 is energised and the end 29 of the armature is attracted towards the coil 30. Movement of the end 29 towards the coil 30 moves the contact 26 away from the contact 28 and eventually the contact 27 encounters the contact 28. When this occurs the coil 31 is energised and the end 29 is moved towards coil 31, thereby breaking the circuit of the coil 31 by the movement of the contact 27 away from the contact 28. Continued movement of the armature 23 in this manner produces vibration sufficient to cause segregation of the concrete into which the container 1 may be inserted.

Use of the apparatus shown in Figures 1 and 2 is effected as follows. The switch 8 is closed and the two-way switch 16 is brought to a position in which the contact 20 encounters the contact 22. The ammeter then indicates a current which depends on the E. M. F. of the battery 11. This E. M. F. varies according to the length of time the battery has been used and in order to ensure that the E. M. F. applied across the electrodes 2 and 3 is always the same for each individual test, the control knob 17A is manipulated until the ammeter indicates a standard current. The position of the two-way switch is then altered so that contact 20 encounters contact 21. The container 1 is then pushed into the concrete mass which it is desired to test, the electrodes 2 and 3 being completely submerged in the concrete. The vibration of the container caused by the motor 5 having the eccentric weight 7 promotes local segregation of the concrete in the vicinity of the container, and as the stones and heavy aggregate sink, a mixture of water, cement and sand rises to the top. As the mixture of water, sand and cement rises to the top the current flowing through the electrodes indicated by the ammeter increases. The container 1 is gradually withdrawn from the concrete until the electrodes 2 and 3 just touch the surface of the concrete, and then the current indicated by the ammeter is read. Actually the operator merely has to read the maximum value indicated by the ammeter, whilst the container is being withdrawn from the concrete, and if the operator is in any doubt as to whether the concrete has been sufficiently segregated, the vibra-

tion is allowed to continue for a further few moments to see if any increase in the value indicated by the ammeter is obtainable.

The water content of the concrete is deduced from the maximum value of current flowing through the electrodes 2 and 3 as indicated by the ammeter 15, by comparing the value with tables or graphs showing the relationship between water-content and the maximum current. Tables or graphs are prepared from data obtained as a result of experimental tests, in which the actual water content of concrete was known, the water being weighed before being mixed with the other constituents of the concrete.

In the instrument described above direct current only has been used, but it will, of course, be appreciated that alternating current could be used instead.

I claim:

1. A method of determining the water content of a mass of fluid concrete which consists in vibrating the fluid concrete until the constituents thereof segregate, the heavier constituents falling to the bottom of the mass whilst the lighter constituents remain at and rise to the upper zone of the mass, and which method further consists in inserting two spaced electrodes in the mass in the zone in which the lighter constituents tend to segregate, a known E. M. F. being applied across the electrodes and measurements being made of the maximum current passing between the electrodes during the vibrating operation, the maximum current value being used as an indication of the water content of the mass of fluid concrete.

2. A method as claimed in claim 1, wherein the determination of the maximum current is made upon the withdrawal of the electrodes from the mass, the withdrawal being made in such direction that the electrodes pass through the zone of the mass containing the least solid constituents.

3. Apparatus for determining the water content of fluid concrete comprising supporting means, a pair of electrodes for insertion in the fluid concrete, said electrodes being located in spaced relation upon the supporting means, a vibrator for vibrating the concrete under test to cause local segregation of the concrete mix in the vicinity of the vibrator, said vibrator being mounted on the supporting means, means for supplying electrical current to the electrodes and means for the measurement of said current.
